ELECTRIC IRON CONTROL

John Wright, Parkland, Md.

Application October 11, 1940, Serial No. 360,845

2 Claims. (Cl. 200—138)

This invention relates to new and useful improvements in electric iron controls, the subject matter here being similar to my application Serial No. 259,278, filed March 1, 1939.

The principal object of the present invention is to provide an electric iron supporting stand which incorporates electric current cut-off means adapted to shut off electricity to the iron when it becomes overheated while resting upon the stand.

Another important object of the invention is to provide an electric iron control which will be automatic in operation.

Another important object of the invention is to provide an electric iron control which will be substantially fool-proof in operation.

Other objects and advantages of the invention will become apparent to the reader of the following specification.

In the drawings—

Figure 1 represents a side elevational view of the control assembly.

Figure 2 is a top plan view.

Figure 3 is a longitudinal sectional view through the shell of the control.

Figure 4 is a horizontal sectional view through the control.

Figure 5 is an end elevational view.

Figure 6 is a cross section on the line 6—6 of Figure 4.

Figure 7 is a fragmentary detailed sectional view showing the rheostat means.

Figure 8 is a fragmentary detailed sectional view fragmentarily showing the switch means and means for adjusting the trip contact.

Figure 9 is a diagrammatic view showing the electrical connections between the electrical devices involved.

Referring to the drawings wherein like numerals designate like parts, it can be seen that numeral 5 denotes a base preferably of some suitable insulation. The top surface of the base 5 has a continuous groove for receiving the lower preferably beaded edge of a shell 6 which tapers to a blunt point 7, at which point in the side walls and top thereof are openings 8 through which light from a lamp 9 in the shell can pass.

U-shaped members 10 attached to the top side of the base 5 are hingedly connected by a pin 11 to the leg members of U-shaped members 12, which, in turn, have upstanding arms 13 formed to engage a horizontal bar 14 of insulation. Bolts 15 are preferably employed for securing the bar 14 to the arms 13.

Numeral 16 generally refers to the switch means which consists of an upstanding contact finger 17 swingably mounted as at 18 on a U-shaped member 19 rising from the base 5 and a spring 20 serves to urge this finger 17 toward a swingable contact finger 21, and against said finger 21 when the upper end of the finger 21 is abutting the free end of a heat responsive thermal element 22, this element 22 being supported by a bracket 23 which has a face portion 24 attached to the base 5. This bracket 23 has a plate portion 25 and a screw or stud 26 is attached to this plate 25 and extends through a slot 27 in a broad portion 28 of a lever 29, the lower portion of which has a foot 30 to which the lower end of the contact finger 21 is pivoted as at 31. The other end of this lever 29 extends through the rear wall of the shell 6 as suggested in Figures 3 and 4 and is there equipped with a knob 32. Obviously by adjusting the lever 29, the finger 21 can be adjusted so that it will not be released until the thermal element 22 has moved to a releasing position under a predetermined temperature.

As can be seen in Figure 8, the bar 14 of insulation extends under the thermal element 22.

The bar 14 is equipped with reset means which consists of an elongated slide 33 operating through a guide 34 located on a bracket 36 which has a horizontal portion 37 along which the slide 33 is slidably supported. This slide 33 has a reduced portion 38 defining a shoulder 39 which abuts the bar 14 of insulation.

The outer end of the slide 33 has a flanged button 40 operative through an opening in the shell 6. Located on the slide 33 and interposed between a collar 41 thereon and the guide 34 is a coiled compression spring 42 which serves to normally maintain the button 40 forced outwardly to the position shown in Figure 7.

Mounted on the forward portion of the base 5 is a lamp socket 43 for supporting a bulb 9. As can be seen in Figure 1, numeral 44 denotes an electric iron positioned on the shell 6. This iron 44 has a cord 45 terminating in a plug 46 which is inserted into a socket 47 on the rear end of the shell 6. As shown in Figure 5, numeral 48 denotes the current supply cord made up of the positive and negative wires 49 and 50 (see Figure 9). The positive wire 49 is connected to one side of a snap switch 51, while the other side of this switch 51 is connected to the positive side of the socket 47. A jumper extends from this side of the socket 47 and is denoted by numeral 52, the same extending to a

contact finger 53 which is in the path of one of the insulation bar supporting arms 13 and against which the arm 13 is held by the spring means 54 of the contact finger 21.

Extending from the negative side of the socket 41 is a wire 55 which connects to the thermal element 22. Extending from the last-mentioned insulation bar supporting arm 13 is a jumper 56 which extends to one side of the lamp socket 43 and from the other side extends a jumper 57 to a binding block 58. From there a connection is made as at 59 to the contact finger 17 and to this is also connected the return wire 50.

It can now be seen that when the switch 51 is closed, current will flow to the positive side of the socket 41, through the iron cord 45 to the conductor 55 and to the thermal element 22 in the position shown in Figure 8, and from there through the contacts 21 and 17 to the negative side 50 of the current supply line 48 without affecting the bulb 9.

However, when heat effects the element 22 so that it lifts and releases the contact finger 21, the finger will be thrown to the right as shown in Figure 9, pressing the bar 14 rearwardly where one of the arms 13 will engage the contact finger 53. Thus electrical connection through the thermal element 22 is broken, but a circuit is established through the contact finger 21 and one arm 13. In other words, as current cannot pass through the iron cord 45 now, in view that there is no circuit through the thermal element 22, the current must flow from the side 49 of the current supply line to the conductor 52, contact element 53, arms 13, jumper 56, lamp 9, jumper 57 and return side 50, thus energizing the lamp to indicate that the iron is cut off.

A spring 13a (see Figure 9) serves to return the bar 14 so as to break the contact 13 related to the spring contact 53 from said spring contact fingers 53 when the member 21 is forced to set position as shown in Figure 8. In other words the spring 13a prevents the arm 13 shown in Figure 9 from returning and contacting the spring contact 53.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A thermal switch comprising a thermal member, a contact, a spring actuated finger held against the contact by the thermal member when the thermal member is contracted, the spring of the finger moving the finger away from the contact when the finger is released by expansion of the thermal member by heat, a hinge member including a part of non-conducting material against which the spring of the finger moves the finger when released by the thermal device, manually operated means for moving the hinge member to press the finger against the contact and to a position where it will be engaged by the thermal member when the same is in normal condition, a second contact against which a conducting part of the hinge member is moved when the hinge member is engaged by the finger and yieldable means for normally holding the hinge member out of engagement with the second contact.

2. A thermal switch comprising a thermal member, a contact, a spring actuated finger held against the contact by the thermal member when the thermal member is contracted, the spring of the finger moving the finger away from the contact when the finger is released by expansion of the thermal member by heat, a hinge member including a part of non-conducting material against which the spring of the finger moves the finger when released by the thermal device, manually operated means for moving the hinge member to press the finger against the contact and to a position where it will be engaged by the thermal member when the same is in normal condition, means for adjusting the finger relative to the thermal member for regulating the time of release of the finger by the thermal element, a second contact against which a conducting part of the hinge member is moved when the hinge member is engaged by the finger and yieldable means for normally holding the hinge member out of engagement with the second contact, said finger adjusting means including a lever to one end of which one end of the finger is pivoted and means for holding the lever in adjusted position.

JOHN WRIGHT.
